(57) **CLAIM**

The ornamental design for a safety gate, as shown and described.

DESCRIPTION

FIG. 1 is a first perspective view of a safety gate showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an opening state of the safety gate thereof;

FIG. 10 is an enlarged view of the selected portion 10 in FIG. 1; and,

FIG. 11 is an enlarged view of the selected portion 11 in FIG. 1.

The broken lines shown in the drawings depict portions of the safety gate that form no part of the claimed design.

1 Claim, 11 Drawing Sheets
